ELECTRICAL SWITCH

Herbert J. Crabbs, Wilkinsburg, Pa., assignor to
Westinghouse Electric & Manufacturing Company,
East Pittsburgh, Pa., a corporation of
Pennsylvania

Application December 31, 1937, Serial No. 182,754

8 Claims. (Cl. 200—149)

The invention relates in general to electrical switches and more particularly to air break switches for opening and closing electrical circuits and for extinguishing the arc formed during circuit interruption.

An object of the invention is the provision of an improved electrical switch that is operable to open the circuit and quickly extinguish the arc and which in the open position provides an air gap in the circuit capable of withstanding high voltages.

Another object of the invention is the provision of an electrical switch embodying an improved contact means and associated arc extinguishing means.

Another object of the invention is the provision of an electrical switch embodying a stationary contact and a movable switch means comprising a movable contact and a movable arc extinguishing structure both of which are mounted for movement together toward and away from the stationary contact, and in which the movable contact is movable a limited amount relative to the arc extinguishing structure.

Another object of the invention is the provision of an electrical switch as described embodying an improved actuating means that is operable during a circuit opening operation to first separate the movable contact from the stationary contact, and to then move both the movable contact and the arc extinguishing structure together away from the stationary contact to open circuit position.

Another object of the invention is the provision of electrical switch as described above in which all of the parts are mounted on a single insulating support and arranged so as to occupy a small amount of space.

Another object of the invention is the provision of an electrical switch embodying an improved switch means for opening and closing the circuit and for extinguishing the arc, and an improved actuating mechanism that is automatically operable to cause the switch means to open the circuit and to reclose the circuit following interruption thereof.

Another object of the invention is the provision of an automatic electric switch as described which also embodies electro-responsive means including a thermal trip element and a magnetic trip element each of which is operable in response to predetermined overload conditions to cause automatic operation of the actuating mechanism to effect opening and reclosing of the switch means.

Another object of the invention is the provision of an automatic switch embodying an im-

proved spring driven actuating mechanism for automatically opening and reclosing the switch means and for holding the switch means in open circuit position after a predetermined number of opening and closing operations.

Another object of the invention is the provision of an improved automatic switch as described above, that is entirely self-contained, all of the parts being mounted within an enclosing casing.

Another object of the invention is the provision of an improved electrical switch which is simple, safe and reliable in operation, which occupies a small amount of space, and which can be manufactured at a relatively low cost.

The novel features that are considered characteristic of the invention are set forth in particular in the appended claims. The invention itself, however, both as to structure and operation, together with additional objects and advantages thereof, will best be understood from the following detailed description of several embodiments thereof when read in connection with the accompanying drawing, in which:

Figure 1 is a vertical sectional view of the electrical switch constructed in accordance with the invention, the switch means being shown in the closed circuit position.

Fig. 2 is a view similar to Fig. 1, showing the switch means in open circuit position during an automatic opening and reclosing operation.

Fig. 3 is a side elevational view of a modification of the invention, the switch illustrated being shown in the closed circuit position, and

Fig. 4 is a view similar to Fig. 3, showing the switch in open circuit position.

Referring to Figs. 1 and 2 of the drawing, the automatic switch illustrated comprises, in general, a casing 7, a stationary contact 9, a movable switch means indicated generally at 11 for opening and closing the circuit and for extinguishing the arc formed during circuit interruption, an actuating mechanism indicated generally at 13 for opening and reclosing the switch means, and electro-responsive means indicated generally at 15 for causing operation of the actuating mechanism in response to predetermined overload conditions.

The casing 7 which is formed of insulating material is cylindrical in shape and has an end wall 17 and a cover (not shown) which is removably mounted on the casing to close the open end thereof. The switch is entirely self-contained, all of the parts thereof being mounted within and protected by the insulating casing 7. A pair of conductors 19 and 21, which form a part

of the circuit controlled by the switch and which are adapted to be connected to the terminals of the switch, extend into the casing 7 through a pair of lead-in bushings 23 which are formed integral with the casing 7. After the conductors 19 and 21 have been inserted through the openings in the bushings 23 and connected to the terminals of the switch, the openings may be sealed in any suitable manner in order to prevent the entrance of moisture in the casing.

The stationary contact 9 which is rigidly secured to a terminal member 25 mounted within the casing, consists of a curved rod of conducting material. The terminal 25 is provided with a terminal lug 27 for receiving the end of the conductor 19 to electrically connect the conductor to the terminal 25 and stationary contact 9.

The movable switch means 11 for opening and closing the circuit and for extinguishing the arc formed during circuit interruption comprises a pair of arms 29 and 31 which are mounted for swinging movement together toward and away from the stationary contact 9 by means of a centrally located pivot stud 33 secured to the end wall 17 of the casing. The arm 29 which is preferably formed of insulating material is pivotally mounted at one end on the stud 33 and carries at its outer end a curved arc extinguishing tube 35. The stationary contact 9 and the tube 35 have the same curvature, the center of which coincides with the center of the pivot stud 33. The tube 35 is provided with a bore 37 for receiving the stationary contact 9, and the length of the tube is such that it encloses the major portion of the stationary contact 9 in the closed circuit position of the switch means, as is shown in Fig. 1. The tube 35 is formed of a suitable insulating material which acts to extinguish the arc formed during circuit interruption. A material known as horn fiber, may be used for the composition of the tube. If desired, the tube 35 may be composed of molded insulating material or a refractory insulating material and the bore 37 thereof lined with an arc extinguishing material such as horn fibre, boric acid compound or other material which gives off a gas when acted on by the arc. The tube functions as an expulsion arc extinguishing device utilizing a blast of gas through the arc to extinguish the same. The gas is produced by action of the arc on the arc extinguishing material of the tube.

The arm 31 which is formed of conducting material is pivotally connected at one end to the end of one arm 39 of a bell crank lever 41 which is pivotally mounted on the pivot stud 33. The outer end of the arm 31 carries a yoke shaped movable contact 43 which is adapted to engage the lower end portion of the stationary contact 9. The arm 31 is connected to the insulating arm 29 for swinging movement therewith by means of a guide bracket 45 carried by the arm 29, the guide bracket 45 being provided with an opening through which the arm 31 extends.

The bell crank lever 41 forms a part of the actuating mechanism to be hereinafter described and this lever is rotatable on the pivot stud 33 a limited amount relative to the insulating arm 29. The arm 47 of the bell crank lever 41 is provided with a projection 49 which engages a projection 51 carried by the insulating arm 29 to limit counter-clockwise movement of the bell crank lever relative to the insulating arm 29. For limiting clockwise rotation of the bell crank lever 41 relative to the insulating arm 29, there is provided a projection 53 carried by the insulating

arm 29 which is adapted to be engaged by the arm 39 of the bell crank lever 41. The bell crank lever 41 is biased to the counter-clockwise limit of its movement relative to the insulating arm 29 by means of a spring 55 which is connected in tension between the arm 47 of the bell crank lever 41 and the insulating arm 29.

When the switch means 11 is in the closed circuit position, as shown in Fig. 1, and the bell crank lever 41 is rotated in a counter-clockwise direction about the pivot stud 33 by the actuating mechanism, the bell crank lever 41 first rotates counter-clockwise relative to the insulating arm 29 which remains stationary. This relative rotation of the bell crank lever 41 moves the contact carrying arm 31 longitudinally relative to the insulating arm 29 to separate the movable contact 43 from the lower end of the stationary contact 9. During this movement an arc is drawn between the movable contact 43 and the end of the stationary contact 9. Continued counter-clockwise movement of the bell crank lever 41 after the projection 49 engages the projection 51, causes counter-clockwise movement of the insulating arm 29 and the contact carrying arm 31 about the pivot stud 33 as an axis to the open circuit position shown in Fig. 2. During this movement of the switch means 11 to open circuit position, the arc extinguishing tube 35 is withdrawn from the stationary contact and the arc is drawn inside of the bore 37 of the tube where it is deionized and extinguished in a well known manner.

When the switch means 11 is in the open circuit position shown in Fig. 2 and the bell crank lever 41 is rotated in a clockwise direction by the actuating mechanism to close the switch, the insulating arm 29 is moved from the open circuit position shown in Fig. 2 to the closed circuit position shown in Fig. 1, the contact carrying arm 31 being carried along with the insulating arm 29 by reason of the bracket 45 which connects the two arms. During this movement, the spring 55 maintains the projection 49 of the bell crank lever 41 in engagement with the projection 51 carried by the insulating arm 29. After the arc extinguishing tube 35 engages the terminal member 25, the continued clockwise movement of the bell crank lever 41 causes the contact carrying arm 31 to be moved longitudinally relative to the insulating arm 29 to effect engagement of the movable contact 43 with the lower end of the stationary contact 9.

The switch means 11 is adapted to be releasably held in closed position by a pivoted latch member 57 which engages a latch pin 59 carried by the bell crank lever 41.

The actuating mechanism indicated generally at 13 for opening and reclosing the switch means 11 comprises a rotatable crank arm 61, a link 63 which connects the free end of the crank arm 61 with the bell crank lever 41 and a spiral spring 65 for driving the crank arm. The crank arm 61 is secured to a barrel 66 which is rotatably mounted on a shaft 67 mounted within the casing, and the free end of the crank arm is pivotally connected to the upper end of the link 63 by means of a pivot pin 69. The lower end of the connecting link 63 is pivotally connected to the end of the arm 47 of the bell crank lever 41 by means of a pivot pin 71. One end of the driving spring 65 is secured to the barrel 66 and the opposite end thereof is rigidly secured to the casing 7 by means of a stud 73. The spring 65 is adapted to be wound up by a suitable key, not shown,

which engages the barrel 66, and the energy stored in the spring 65 is adapted to rotate the crank arm 61 in a counter-clockwise direction about the shaft 67 when the mechanism 13 is released. The crank arm 61 and the link 63 form a toggle linkage which assumes approximately one dead center position when the switch is closed, as shown in Fig. 1, and approximately the opposite or extended dead center position when the switch means is in the open circuit position. The actuating mechanism is releasably held in inoperative position by means of the pivoted latch member 57 which in its latching position engages the pin 59 carried by the bell crank lever 41. The latch member 57 thus serves to releasably hold the switch means 11 in closed circuit position and the actuating mechanism in an inoperative condition.

When the latch member 57 is moved to its released position by the electro-responsive means 15 to release the bell crank lever 41, the spring 65 drives the crank arm 61 in a counter-clockwise direction about the shaft 67. The counter-clockwise movement of the crank arm during the first 180° of its travel causes the bell crank lever 41, which is connected thereto by the link 63, to rotate in a counter-clockwise direction. This rotation of the bell crank lever 41 effects movement of the switch means 11 to open circuit position in the manner previously described. The continued rotation of the crank arm 61 through the next 180° of its movement after the switch means 11 has moved to the open circuit position shown in Fig. 2, causes the bell crank lever 41 to be rotated in a reverse or clockwise direction to automatically effect reclosing of the switch means 11 in the manner previously described. When the switch means 11 reaches closed circuit position, the pin 59 of the bell crank lever is re-engaged by the latch member 57 to hold the switch means in closed circuit position and the actuating mechanism in the position shown in Fig. 1, if the overload condition which caused movement of the latch member 57 to its releasing position no longer exists. The toggle formed by the crank arm 61 and the link 63 provides a certain amount of time delay as it passes through its extended dead center position, reducing the speed of rotation of the bell crank lever 41, thus permitting the fault condition to be cleared if it is of a transitory nature before the switch is reclosed. If desired, the reclosing movement of the switch means 11 may be further retarded in any well known manner to provide a longer time delay prior to reclosing of the circuit.

A lock-out means is provided for preventing reclosure of the switch means 11 after a predetermined number of opening and closing operations have occurred. The lock-out means comprises the reduction gear 75 which is driven by a pinion gear 77 which is secured to the crank arm 61 for rotation therewith. The gear 75 carries a stop pin 79 which engages the right hand side of a stop member 81 carried by the casing 7 after a predetermined number of opening and reclosing operations have occurred. The stop member 81 is manually movable out of the way of the pin 79 to permit reclosing of the switch means 11 after the fault condition has been cleared. The lock-out means prevents the spring 65 from being unwound more than a predetermined amount so that sufficient reserve spring effort is provided for the final reclosing operation after the stop member 81 has been moved to an inoperative position.

The electro-responsive means for moving the latch member 57 to releasing position to cause operation of the actuating mechanism 13 comprises, in general, a thermal trip means in the form of a bimetallic strip 83, and an electromagnetic trip means consisting of an armature 85 and a stationary core 87. The stationary core 87 and the bimetallic trip element 83 are mounted on a bracket 88 secured to the end wall 17 of the casing 7. The core 87 is U-shaped and is adapted to cooperate with the armature 85 which is secured to one leg 90 of the latch member 57; the latch member being pivotally mounted on a pivot stud extending from the end wall 17 of the casing 7. The latch member 57 is also provided with a leg 89 which extends on the other side of the pivot axis of the latch member from the leg 90 which carries the armature 85. The leg 89 of the latch member 57 is adapted to be engaged by the projection 91 carried by the free end of the bimetallic trip element 83. The latch member 57 is biased to latching position by means of a spring 93 connected at one end to the leg 89 of the latch member and having its other end secured to a stud carried by a casing 7.

The bimetallic trip element 83 and the electromagnetic trip means comprising the armature 85 and the core 87 are each energized in response to the current flowing in the circuit by means of a heater strip 95. The heater strip 95 is secured at one end to the bracket 88 and at its opposite end to a bracket 97 which supports a terminal lug 99. A portion of the heater strip extends between the legs of the U-shaped core 87 and for a considerable portion of the length of the bimetallic trip element 83. One end of the heater strip 95 is electrically connected to the terminal lug 99 which receives the conductor 21, and the other end of the heater strip is electrically connected to the contact carrying arms 31 by means of a flexible shunt conductor 101.

The circuit through the switch extends from the left-hand terminal 25 through the stationary contact 9, movable contact 43, contact carrying arm 31, flexible shunt conductor 101 and through the heater strip 95 to the right-hand terminal lug 99.

The operation of the switch is briefly as follows. When an overload of predetermined magnitude and duration occurs in the circuit controlled by the switch, the bimetallic trip element 83 is heated a sufficient amount to flex in the direction of the latch member 57. This flexing of the bimetallic trip element moves the latch member 57 to released position, as shown in Fig. 2, to effect release of the switch means 11 and the actuating mechanism 13. When the actuating mechanism 13 is released the crank arm 61 is driven by the spiral spring 65 in a counter-clockwise direction to effect counter-clockwise movement of the bell crank lever 41. The counter-clockwise movement of the bell crank lever 41 effects separation of the movable contact 43 from the stationary contact 9 and then causes counter-clockwise movement of the switch means 11 comprising the arms 29 and 31 to the open circuit position shown in Fig. 2. During this movement of the switch means 11 to open circuit position, the arc is extinguished by means of the arc extinguishing tube 35. The continued counter-clockwise movement of the crank arm 61 after the switch means has reached full open position, as shown in Fig. 2, causes reverse or clockwise rotation of the bell crank lever 41 to effect reclosing of the switch means 11 and cir-

cuit. If the overload condition which causes release of the latch member 57 no longer exists, the latch member reengages the pin 59 carried by the bell crank lever 41 to hold the switch means 11 in closed circuit position and the actuating means in the inoperative position as shown in Fig. 1. If the overload condition still exists, the spring 65 continues to drive the crank arm 61 to cause another opening and reclosing operation of the switch means. After a predetermined number of opening and reclosing operations have occurred, the lock-out means comprising the pin 79 and the top member 81 operate to prevent reclosure of the switch means 11.

When an overload of higher magnitude or a short circuit occurs in the circuit, the electromagnetic means comprising the core 87 and the armature 85 is energized a sufficient amount to move the armature 85 to attracted position. This effects release of the latch member 57. The release of the latch member 57 by the electromagnetic means causes the actuating mechanism 13 to effect automatic opening and reclosing of the switch means 11 in the manner previously described in connection with the tripping by the bimetallic trip element.

A modification of the invention is illustrated in Figs. 3 and 4 of the drawing. In this modification the switch means and arc extinguishing means are substantially similar to the corresponding means described in the original embodiment. The modified form of switch comprises, in general, an insulating support 105, a stationary contact 107, switch means indicated generally at 109 and an actuating means for the switch means indicated generally at 111. The insulating support 105 consists of a column formed of vitreous insulating material such as porcelain having a mounting bracket 113 secured thereto intermediate its ends. The bracket 113 is provided with a clamp means 115 for mounting the switch on a cross arm of a pole, tower or other form of support. A pair of terminal members 117 and 119 are rigidly secured to the opposite ends of the column 105 and each of the terminal members is provided with a terminal lug 121 for connecting the switch in an electrical circuit.

The stationary contact 107 consists of a curved rod of conducting material secured at one end to the terminal member 117.

The switch means 109 comprises a pair of arms 123 and 124 mounted for swinging movement together toward and away from the stationary contact 107. The arm 123 is of insulating material and is pivotally mounted on a pivot pin 127 carried by a bracket 129 secured to the lower end of the column 105. The upper end of the insulating arm 123 carries a curved arc extinguishing tube 131. The curvature of the tube 131 and the stationary contact member 107 are the same, the center of which curvature coincides with the center of the pivot pin 127. The tube 131 is composed of suitable insulating material similar to the material of the tube 35 described in connection with the original embodiment of the invention. The tube 131 is provided with a bore 133 for receiving and enclosing a major portion of the stationary contact 107 in the closed circuit position of the switch means. The arm 124 which is of the conducting material is pivotally connected at its lower end to a pivot pin 135 which extends transversely between the legs of a yoke shaped actuating member 137. The actuating member, in turn, is pivotally mounted at

its lower end by means of the pivot pin 127 which supports the insulating arm 123. The upper end of the arm 124 carries a yoke shaped movable contact 139 which is adapted to engage the outer end portion of the stationary contact 107 in the closed circuit position of the switch. The contact carrying arm 124 is electrically connected at its lower end to the terminal member 119 by means of a flexible shunt conductor 141.

10 The actuating member 137 which forms the actuating means for the switch is provided with an operating eye 143 adapted to be engaged by a hook stick for operating the switch means 109 to open or to closed circuit position.

15 A cover or shroud 145 is mounted on the upper end of the column 105 for protecting the stationary contact and switch means.

20 The circuit through the switch extends from the upper terminal 117, through the stationary contact 107, movable contact 139, contact carrying arm 124 and flexible shunt conductor 141 to the lower terminal member 119.

25 The operation of the switch is briefly as follows. To open the switch the operator inserts a hook stick in the operating eye 143 of the actuating member 137 and exerts a downward pull on the actuating member to cause that member to rotate in a counterclockwise direction about the pivot axis 127.

30 During the first portion of the counterclockwise movement of the actuating member 137, the contact carrying arm 124 is moved longitudinally downwardly relative to the insulating arm 123 to separate the movable contact 139 from the end of the stationary contact 107.

35 The continued counterclockwise movement of the actuating member 137 swings both the arms 123 and 124 in a counterclockwise direction about the pivot axis 127 to the open circuit position shown in Fig. 4. During this movement, the arc is drawn into the bore 133 of the arc extinguishing tube 131 and quickly extinguished in a well known manner. It will be noted that in the open circuit position of the switch a large air gap is provided between the movable contact 139 and the stationary contact 107, that is capable of withstanding high voltages.

40 To reclose the switch the actuating member 137 is moved by the hook stick from the position shown in Fig. 4 in a clockwise direction about the pivot axis 127 to the position shown in Fig. 3. This movement of the actuating member swings the connected arms 123 and 124 in a clockwise direction. After the arc extinguishing tube 131 engages the terminal member 117, the continued movement of the actuating member 137 causes upward longitudinal movement of the contact carrying arm 124 relative to the insulating arm 123 to effect engagement of the movable contact 139 with the outer end of the stationary contact 107.

45 50 55 60 65 70 75 The invention in both of the embodiments disclosed provides an electrical switch that is simple, safe and reliable in operation, compact so that it occupies a small amount of space, and that can be manufactured at a relatively low cost. All of the operative parts of the switch are supported on a single insulating support. The movement of both the movable contact and the arc extinguishing structure away from the stationary contact provides a relatively large air gap between the movable contact and the stationary contact which is capable of withstanding high voltages.

70 75 The original embodiment of the invention illustrated in Figs. 1 and 2 and described in con-

nection therewith provides an automatic switch that is operable to open the circuit either in response to a lower magnitude overload of prolonged nature, or a heavy overload or short circuit condition. The switch means is automatically reclosed following extinguishment of the arc so as to assure continuity of service in the event that the overload condition is of a transitory nature. The switch embodies a very simple and effective actuating mechanism that is spring driven for opening and reclosing the switch means, thus eliminating the necessity of any auxiliary apparatus and control circuits. The automatic switch is entirely self-contained and enclosed.

While the invention has been disclosed in accordance with the provisions of the patent statutes, it is to be understood that various omissions, substitutions and changes may be made without departing from the spirit of the invention. It is desired, therefore, that the appended claims be given the broadest construction permissible in view of the prior art.

I claim as my invention:

1. In an electrical switch, a stationary contact member, switch means movable to open and to closed circuit position for opening and closing the circuit and for extinguishing the arc formed during circuit interruption comprising a movable contact member and a movable arc extinguishing device mounted for movement together away from and toward said stationary contact, said movable contact member being movable a limited amount relative to said arc extinguishing device.

2. In an electrical switch, a stationary contact member, switch means movable to open and to closed circuit position for opening and closing the circuit and for extinguishing the arc formed during circuit interruption comprising a movable contact member and an arc extinguishing device mounted for swinging movement together away from and toward said stationary contact, said movable contact member being movable a limited amount relative to said arc extinguishing device; and a single insulating support on which said stationary contact and switch means are mounted.

3. In an electric switch, a stationary contact member, switch means movable to open and to closed circuit position for opening and for closing the circuit and for extinguishing the arc formed during circuit interruption, said switch means comprising an arm carrying a movable contact and a second arm carrying an arc extinguishing device, both of said arms being mounted for swinging movement together toward and away from said stationary contact, said movable contact being movable a limited amount relative to said second arm.

4. In an electrical switch, a stationary contact, switch means movable to open and to closed circuit position for opening and closing the circuit and for extinguishing the arc formed during circuit interruption comprising a movable contact member and a movable arc extinguishing device, and actuating means operable during a circuit opening operation to first separate said movable contact member from said stationary contact while said arc extinguishing device remains stationary, and to then move said arc extinguishing device and movable contact member together to

open circuit position away from said stationary contact.

5. In an electric switch, a stationary contact member, switch means movable to open and to closed circuit position for opening and closing the circuit and for extinguishing the arc formed during circuit interruption comprising an arm carrying a movable contact and a second arm carrying an arc extinguishing device, both of said arms being mounted for swinging movement together toward and away from said stationary contact and said contact carrying arm having limited movement relative to said second arm, and actuating means operable during a circuit opening operation to first move said contact carrying arm relative to said second arm to separate said movable contact from said stationary contact, and to then move both said arms together to open circuit position away from said stationary contact.

6. In an electrical switch, a stationary contact member, switch means movable to open and to closed circuit position for opening and closing the circuit and for extinguishing the arc formed during circuit interruption comprising a movable contact and a movable arc extinguishing tube within which said stationary contact member extends in the closed circuit position of the switch means, said movable contact member and tube being mounted for movement together toward and away from said stationary contact, and said movable contact member being movable a limited amount relative to said arc extinguishing tube.

7. In an electric switch, a stationary contact member, switch means movable to open and to closed circuit position for opening and for closing the circuit and for extinguishing the arc formed during circuit interruption comprising an arm carrying a movable contact and a second arm carrying an arc extinguishing tube within which said stationary contact member extends in the closed circuit position of the switch means, said arms being mounted for swinging movement together toward and away from said stationary contact and said contact carrying arm being movable longitudinally relative to said second arm to separate said movable contact from said stationary contact, and actuating means operable during a circuit opening operation to first effect longitudinal movement of said contact carrying arm relative to said second arm to separate said movable contact from said stationary contact, and to then swing both said arms away from said stationary contact to open circuit position.

8. In an electrical switch, a stationary contact, switch means movable to open and to closed circuit position for opening and closing the circuit and for extinguishing the arc formed during circuit interruption comprising a movable contact member and a movable arc extinguishing device, and actuating means operable during a circuit opening operation to first separate said movable contact member from said stationary contact while said arc extinguishing device remains stationary, and to then move said arc extinguishing device and movable contact member together to open circuit position away from said stationary contact, and an enclosed protecting casing within which said stationary contact, switch means, and actuating means are mounted.

HERBERT J. CRABBS.
